UNITED STATES PATENT OFFICE.

DEMSEY FOREST, OF MOTTOOMOSA, TEXAS.

IMPROVEMENT IN MACHINES FOR BENDING STIRRUPS.

Specification forming part of Letters Patent No. 99,303, dated February 1, 1870.

To all whom it may concern:

Be it known that I, DEMSEY FOREST, of Mottoomosa, in the county of Alascosa and State of Texas, have invented a new and Improved Stirrup-Machine; and I do hereby declare that the following is a full, clear, and exact description thereof, by which those skilled in the art can make and use the same, reference being had to the accompanying drawings, forming part of this specification.

The object of this invention is to provide a simple and efficient machine for bending and shaping stirrups for saddles.

The invention comprises a clamping-vise with jaws of peculiar construction and adaptation for bending the thin wood plates or sheets around the lever-former, which is used by the operator to bend the blanks down into the forming-recesses of the jaws, and hold them until the said jaws are clamped together and the blanks reduced to the finished form and secured to the blocks by which the suspending-straps are connected, all as hereinafter more fully specified.

Figure 1 represents a side elevation of my improved machine; and Fig. 2 represents a front elevation of the same, partly broken out.

A represents a pair of clamping-jaws, pivoted to the support B at C, and provided with a clamping-screw, D, in a manner similar to bench-vises, except that both jaws are pivoted. I may, however, use vises with one fixed jaw; but I prefer to have them both movable. Between the said jaws springs E may be arranged in any suitable way to throw them open when the screw is retracted. The upper ends

of these jaws are recessed in the faces fronting each other, the said recesses being, when the jaws are clamped together, of the form required to constitute a mold corresponding to the exterior form of the stirrups below the necks, by which the straps are connected.

F represents a forming-lever, arranged to engage in a notch in a post at G, for a fulcrum for pressing the blanks down into the said mold formed in the tops of the jaws. This lever, at the place where it passes through the mold, is designed to be in cross-section of the form corresponding to the interior of the finished stirrups, as shown at H. The blanks of the stirrups, which are to be made of thin sheets or strips of wood, first being cut or otherwise shaped as required, are placed upon the tops of these jaws A, over the recesses or mold, the jaws being sufficiently opened, and the forming-lever is used to press the blanks down into the recesses. The jaws are then screwed up and the said blanks shaped around the former, as shown at I, after which the blocks or necks K for the connection of the suspending-straps are inserted and riveted. The former is then withdrawn and the finished stirrup discharged.

Having thus described my invention, I claim as new and desire to secure by Letters Patent—

The improved method of forming stirrups by means of the clamping-jaws, recessed as described, and the forming-lever F, all substantially as specified.

DEMSEY FOREST.
